UNITED STATES PATENT OFFICE.

ALBERT REDDLE THOMSON, OF PLANTSVILLE, CONNECTICUT.

PICKAX.

1,244,662.

Specification of Letters Patent.

Patented Oct. 30, 1917.

Application filed July 29, 1916. Serial No. 112,025.

To all whom it may concern:

Be it known that I, ALBERT REDDLE THOMSON, a citizen of the United States, residing at Plantsville, in the county of Hartford and State of Connecticut, have invented certain new and useful Improvements in Pick-axes, of which the following is a specification.

My invention relates to improvements in pickaxes, and particularly to the type wherein the bits are removably connected to the body portion and the object of my improvement is to provide locking means for preventing the accidental and unintentional removal of the bits.

In the accompanying drawing:

Figure 1 is a side elevation of my improved pickax.

Fig. 2 is a plan view of the same.

Fig. 3 is a side elevation of the body portion.

Fig. 4 is a similar view of one of the bit members.

Fig. 5 is a side elevation on an enlarged scale of the body portion and parts of the two bit members.

Fig. 6 is a sectional view on the line $\alpha\alpha$ of Fig. 5.

Fig. 7 is a sectional view corresponding to Fig. 6, showing a modification of the locking device.

My improved pickax comprises a body portion 10 provided with a handle aperture 11 in which is housed one end of the handle 12, and a pair of bit portions 13 that extend outwardly from the body portion 10 on opposite sides of the handles 12 in the usual manner for pickaxes.

The bit portion 13 is part of a bit member 15, the inner end of which is in the form of a head 16 of tapered form that fits in a correspondingly tapered socket 17 in the body portion 10.

The socket 17 is provided in a lateral branch 18 of the body portion 10, and the said branch 18 is provided with a slot 19 extending through the two opposite faces thereof, and directed longitudinally, for receiving a wedge for the purpose of driving out the tool or bit member 15 when it is desired to remove the same, and as is usual in devices of the kind shown and described.

The tapered form of the head 16 and the socket 17 serves generally to hold the bit member 15 connected to the body portion 10. In special cases however and under severe

conditions of use I find it desirable to provide special locking means for locking the bit member in place so as to positively hold the same in place, and such locking means I provide in the following manner:

On one face of the branch 18 along the border edges of the slot 19 I provide a set of teeth 20 that serves as the locking means so far as the body portion is concerned.

On the bit member 15 I provide locking means that coöperate with the teeth 20 and travel with the bit member comprising a dog 21 that bridges the slot 19, having teeth 22 on the lower side for engaging with the teeth 20, and having a hole 23 that is a fit for the bolt 24. The said bolt 24, as shown, has the bolt head 25 on the face of the branch 18 opposite that having the teeth 20, bridging the slot 19, the body portion fitting and passing through a hole 26 in the head 16 of the bit member 15, and also through the hole 23 in the dog 21, and has a wing nut 27 mounted on the threaded end, and interposed between the said wing nut 27 and the dog 21 is a spring washer 28.

By using the spring washer 28 as described means are provided for permitting the dog 21 to slide along over the teeth 20 as the head 16 is driven farther into the socket 17 and at the same time the wing nut 27 can be tightened snugly against the spring washer 28 so that the teeth 22 of the dog will be in firm contact with the teeth 20 of the body portion 10, and will positively prevent the removal of the bit member 15 while the dog is in the position described.

When it is desired to remove the tool the bolt 24 is removed after which the tool can be driven out by the use of a wedge in the usual manner.

In the modification shown in Fig. 7 a construction is provided in which the dog 21 is dispensed with and in lieu thereof the head 25^a of the bolt 24^a is of special form, suitably to provide teeth 22^a on the inner face thereof.

The teeth 20^a on the branch 18^a that coöperate with the teeth 22^a on the bolt 24^a are on the side face of the said branch 18^a opposed to the head 25^a, as shown, and the portion 29 of the side face opposed to the spring washer 28 is smooth, suitably to provide a sliding, bearing face for the said spring washer 28.

The particular form of the head 25^a shown

comprises a curved recessed form for the inner face 30 of the head 25^a.

The curvature of the face 30 is of high degree and uniform from edge to edge, leaving the edge portions 22^a at the junction with the two end walls 31 of the head 25^a in the form of a relatively sharp angle, and of suitable form to serve as teeth in coöperation with the teeth 20^a provided on the 10 branch 18^a of the body portion 10^a.

In use, as in other style shown and described, as the head is entered within the socket 17 the bolt 24^a travels with the head and the teeth 22^a engage successively with 15 different teeth 20^a, and a positive locking means are provided for preventing the return movement of the head without releasing the wing-nut.

I claim as my invention:

20 1. A pickax comprising a body portion having a tool receiving socket, a bit member having a head fitting the said socket, the said body portion having a slot opening into the said socket, the border wall of the 25 said slot on one face of the said body portion having a set of teeth, the said head having a hole in registration with the said

slot, a locking member having teeth for coöperating with the said teeth on the body portion and means for operatively mounting the said locking member on the said head, comprising a bolt passing through the said hole and also through the said slot, and a spring washer and nut mounted on the said bolt. 30

2. A pickax comprising a body portion having an elongated, tapered socket and a removable bit member having a head fitting the said socket, and a checking device for permitting a slight inward movement 40 of the said head relatively to the said socket when the said head is positioned in the said socket and positively preventing a return movement thereof, the said checking device comprising a set of fixed teeth on the said body portion, a dog having teeth for coöperating with the said teeth on the body portion, and yielding means serving to connect the said dog with the said head. 45

ALBERT REDDLE THOMSON.
